(57) **CLAIM**

The ornamental design for scissors, as shown and described.

DESCRIPTION

FIG. 1 is a front, left side and top perspective view of scissors, showing our new design;
FIG. 2 is a left side view thereof;
FIG. 3 is a rear view thereof;
FIG. 4 is a right side view thereof;
FIG. 5 is a front view thereof;
FIG. 6 is a top view thereof; and
FIG. 7 is a bottom view thereof;
FIG. 8 is a cross-sectional view along lines 8-8 of FIG. 2;
FIG. 9 is a cross-sectional view along lines 9-9 of FIG. 2;
and,
FIG. 10 is a cross-sectional view along lines 10-10 of FIG. 4.

1 Claim, 10 Drawing Sheets---
